UNITED STATES PATENT OFFICE.

GEZA J. HAVRILLA, OF ERIE, PENNSYLVANIA.

TAILOR'S DRAFTING-CHART.

1,168,803.

Specification of Letters Patent. Patented Jan. 18, 1916.

Application filed February 5, 1915. Serial No. 6,296.

To all whom it may concern:

Be it known that I, GEZA J. HAVRILLA, a citizen of the United States, residing at Erie, in the county of Erie and State of Pennsylvania, have invented certain new and useful Improvements in Tailors' Drafting Charts; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to making of garment patterns, and the object thereof is to make a chart, and formulate a system, to be used with said chart, whereby garment patterns may be laid out according to any desired bust measure, or which may be used to lay out garment patterns according to special measure.

The features of my invention are herein-after pointed out and explained and are illustrated in the accompanying drawing, in which:—

Figure 1, illustrates the right hand part of my improved chart for laying out garment patterns. Fig. 2, illustrates that portion of my improved chart broken off at the left hand side of Fig. 1.

I construct this chart as follows, viz: At the right hand edge of a sheet of paper I make a line A—B, which represents the center of the back of a garment; the point A, being at the neck-line and the point B, the lower end of said line, which may be extended to any desired length. For the purpose of laying out the chart I extend the line A—B, somewhat above the point A, and from a point on this extension, three quarters ($\frac{3}{4}$) of an inch above the point A, I draw a line B', at right angles thereto, across the top of the paper. At a point on the line B', nine and five-eighths ($9\frac{5}{8}$) inches from the line A—B, I place a point c, and on the line A—B, between the line B', and the point A, one half ($\frac{1}{2}$) inch above the point A, I place a point c', and from the point c, to the point c', I draw a line C. At a point on the line C, one and one half ($1\frac{1}{2}$) inches from the line A—B, I locate one end of a neck-scale C', said neck-scale C', being one and five-eighths ($1\frac{5}{8}$) inches in length, the same being sub-divided as may be desired; but I prefer fourteen sub-di-

visions. However, for the purpose of making a Patent Office drawing, I have shown but seven sub-divisions, numbered as follows: twenty-four, twenty-eight, thirty-two, thirty-six, forty, forty-four, forty-eight, while on the large chart they would be numbered, twenty-four, twenty-six, twenty-eight, thirty, thirty-two, thirty-four, thirty-six, thirty-eight, forty, forty-two, forty-four, forty-six, forty-eight, fifty, each of said numbers representing a bust measure of as many inches. I next make a point a', five and one-half inches below the point A, in the back-line A—B, from which I extend a right angle line, (see broken line a²) which indicates the depth of the arm-hole, in the smallest garment for which the pattern is adapted, below the point A. From the line A—B, I measure along the broken line a², a distance of twelve inches, being one half of the smallest bust measure, to a point a³. I then rule parallel lines below the line a², one-eighth of an inch apart, one line for each size of bust; said sizes being in inches, from twenty-four to fifty; the last line representing the fifty inch bust measure, measuring twenty-five inches from the line A—B. From the outer end of the last or fifty-inch bust line, I draw a line D, to the point a³, on the broken line a²; the intersections of the line D, with the line a², and the parallel broken lines thereunder, indicate the different bust measures from twenty-four inches to fifty inches. I next measure forward eight and one-eighth inches on the line a², from the line A—B, and make a point a⁴, thereon, I then measure forward on the lower-most of said parallel lines representing the fifty-inch bust measure, a distance of fifteen and three-eighths ($15\frac{3}{8}$) inches from the line A—B, where I make a point a⁵, and I draw a line E, from the point a⁴, to the point a⁵, which crosses the intervening parallel bust measure lines, said intersections forming a scale E, by which the front of the arm-hole may be established. I then make a point b, one and one-quarter ($1\frac{1}{4}$) inches back on the line a², from the point a⁴; and I make a point b', on the lower-most parallel line representing a fifty-inch bust measure two and one-quarter ($2\frac{1}{4}$) inches back from the point a⁵, and then draw a line F, from the point b, to the point b', the same crossing the intervening parallel bust measure lines; said intersections being the sub-divisions of said

line F, into a scale for locating the lower edge of the arm-hole opening, and also the upper end of the side seam of the garment. I then make a point b^2 , on the line a^2 , four and one half ($4\frac{1}{2}$) inches from the point a' , on the line A—B, and on the lower-most of said bust measure lines representing a fifty inch bust, I make a point b^3 , eight and three-eighths ($8\frac{3}{8}$) inches from the back line A—B, and I then draw a line G, from the point b^2 , to the point b^3 , crossing the intervening bust measure lines; said intersections of the line G, and the several bust measure lines forming a scale from apparently which the rear of arm-hole opening may be located, as hereinafter described.

The intersections of the lines D, E, F and G, with the parallel bust measure lines, are respectively numbered from twenty-four to fifty, although the drawing in this application only shows every other size, because of the fact that in reducing the chart to Patent Office size, it was necessary to omit every alternate bust measure line. I next draw a straight line H, from the point a^3 , in the scale D, to the point twenty-four in the scale C', and I draw a straight line H', from the outer or lower end of the line D, to the point marked fifty, on the neck-scale C'. I then make a point h , on the line H, four inches downward from the point twenty-four in the neck-scale C'. I then make a point h' , on the line H', seven inches downward from the point fifty on the neck-scale C', and draw a line H^2 , from the point h , to the point h' , and then divide said line into a scale, having twenty-seven equally spaced sub-dividing points including the terminal points h , and h' , which are numbered from twenty-four to fifty inclusive. I then place a point d , on the line A—B, one and three quarters ($1\frac{3}{4}$) inches above the point a' , thereon; and draw a line I, from the point e , in the line C, to the point d , in the line A—B; and on the line I, I place a point d' four inches downward thereon from the point e . I then place a point d^2 , on the line A—B, one and one-quarter ($1\frac{1}{4}$) inches above the point a' , on said line. I then draw a straight scale line J, from the point A, through the point c , the same extending beyond the point c , nine and one-quarter ($9\frac{1}{4}$) inches, which is sub-divided into twenty-seven points, including the point c , which are numbered from twenty-four to fifty inclusive. From the terminal point of the scale J, indicated by the number fifty, which is broken off in Fig. 1 and shown in Fig. 2, I draw a line I', to the point d^2 , in the line A—B. I then make a point d^3 , in the line I' seven inches backward from the point marked fifty in the scale J, and draw a line J', from the point d' , to the point d^3 , which I sub-divide into twenty-seven points including the points d' and d^3 ,

and numbered from twenty-four to fifty, inclusive. On the line B', two inches to the left of the point c , I commence a bust seam scale K, which is eleven and three-eighths ($11\frac{3}{8}$) inches long and is equally sub-divided by twenty-seven points numbered from twenty-four to fifty. Underneath the point c , one-quarter inch, I place a point k , and two and three-quarters ($2\frac{3}{4}$) inches underneath the point fifty on the scale J, I make a point k' , and from the point k , to the point k' , I draw a line K'. This line K', is subdivided by placing scale points thereon perpendicularly above each of the scale points on the line D, as shown by the line k^2 . At a point on the line A—B, five and one-half ($5\frac{1}{2}$) inches below the point a' , I place a point R, which indicates the waist line for a twenty-four inch bust measure garment; and from the point R, I project a line R', forward at right angles to the line A—B, a distance of twelve inches to a point r , which is one-half of the waist line for size twenty-four. Underneath the line R' and parallel therewith, I place parallel lines r' , which are preferably one-half inch apart, which gradually become closer together as they reach the size fifty at the extreme bottom of the waist line scale. On each of the parallel lines underneath the line R', I measure one-half of each succeeding size from twenty-four to fifty, and I then draw a line R^2 , through those points, which establishes the waist line scale. I place point R^3 , on the line R', six and three-eighths ($6\frac{3}{8}$) inches from the point R, and on the waist line for size twenty-nine, I place a point R^4 , seven and five-eighths ($7\frac{5}{8}$) inches from the line A—B. On the waist line for size thirty-six, I place a point R^5 , nine inches from the line A—B; and on the waist measure for size fifty, I place a point R^6 , twelve and one-quarter ($12\frac{1}{4}$) inches from the line A—B. I then draw a line through the points R^3 , R^4 , R^5 and R^6 , which intersects all of the waist measure lines from twenty-four to fifty; said intersections being numbered from twenty-four to fifty, and form the scale side-line Q, for the side seams of the garment.

At the point B, five and one-half inches below the point R, I draw a right angle line S, seven and three-eighths ($7\frac{3}{8}$) inches to a point s , which is scale for front hip measure for size twenty-four. Underneath the line S, I make a series of parallel lines numbered from twenty-four to fifty, and each of which is five and one-half ($5\frac{1}{2}$) inches below the correspondingly numbered waist measure line. Line twenty-nine is eight and three-quarters ($8\frac{3}{4}$) inches long to the point s' ; line 36 is ten and three quarters inches to the point s^2 , and line fifty is thirteen and one-half inches long to the point s^3 . I draw a line S', through the points s , s^2 ,

s' , s^2 and s^3 , the intersections of which line with the hip measure lines, being numbered from twenty-four to fifty, forms the hip measure scale S' . Scale T , is formed by drawing lines T' , through the respective scale points in scale F and scale Q , extending same downward to cross each of said hip measure lines below the line S , and the points of crossing being numbered from twenty-four to fifty, and forms the scale T , for the lower end of side seam over hip.

In making my improved chart I perforate the paper at each scale point numbered from twenty-four to fifty, so that when the chart is used to lay out a pattern, the pattern paper may have small holes punched or otherwise marked therein through the perforated scale points on the chart.

To make a pattern by bust measure I lay my chart upon the pattern paper; then for making a garment pattern for twenty-four bust measure, for example, I perforate or otherwise mark the pattern paper through the perforated points A , B , the point B , being on the line A — B , in line with the points twenty-four in the scales S' and T , marks the lower end of the garment, and the point A , indicates the neck-line at the middle of the back. I then perforate the pattern paper through all of the points numbered twenty-four in the neck-scale C' , the scales H^2 , J , J' , D , E , F , G , R^2 , Q , S' and T , thus marking on the pattern paper the points A , B , c , c^2 , d' , h , a^4 , b , b^2 , a^3 , R^3 , r , and 24, in each of said scales. I then draw a line from A , to B ; a curved neck line 2, from A , to point c^2 ; a straight shoulder line 3, between points c^2 , and h ; an elliptically curved line 4, from the point h , in the scale H^2 , through the point b , of the scale F , and to the point d' , in the scale J' ; to assist in laying out this arm-hole line 4, a line may be drawn from the point b^2 , on the scale G , to the point h , on the scale H^2 , and a short line may be squared up from the point a^4 , at the top scale E , which lines will assist in laying out the arm-hole line 4. The points b , d and h , indicate the upper and lower extremes of the arm hole. From the point d' , to the point c , I draw the front shoulder line 5, which will be of the same length as the rear shoulder line 3. From the point c , to the point k^2 , in the scale K' , I draw the front neck-line 6. From the point k^2 , I draw the front line k^3 , downward through the points a^3 and r , to the bottom of the garment pattern, indicated by the line S , drawn through the points numbered twenty-four in the scales S' and T . The result will be a pattern for the smallest size garment for children. Larger size patterns can be laid out by using a larger bust measure, and following the corresponding size in all of the scales.

Having thus shown and described the con-

struction and method of using my improved chart so that others can construct and utilize the same, what I claim as new and desire to secure by Letters Patent is:—

1. A chart for designing garment patterns having thereon a line representing the center back-line the upper end of which indicates the neck-line, a series of points on said back-line from which bust measurement lines are projected at right angles to said back-line a distance of one-half of the bust measurement and terminate in a bust scale, a rear neck scale on line C , commencing at the point c^2 , thereon, and extending forwardly therefrom; a rear shoulder scale extending from a point in line H , to a point in line H' ; a front neck scale commencing at the point c , in line J , and extending forwardly thereon; and a front shoulder scale extending forwardly from a point in line I , to a point in line I' , so arranged and positioned with relation to each other that the front and rear shoulder lines of a pattern may be determined therefrom, substantially as set forth. 70

2. A chart for designing garment patterns having thereon a line representing the center back-line, the upper end of which indicates the back neck-line, a series of bust measure points on said line, from which bust measure lines are projected at right angles to said back-line a distance of one-half of a bust measure and terminate in a bust measure scale, a rear-neck scale commencing at a point c^2 , on the line C , and extending forwardly thereon; a rear shoulder scale commencing at the point h , in the line H , and extending forwardly to the point h' , in the line H' ; a front neck scale commencing at the point c , in the line J , and extending forwardly therefrom; and a front shoulder scale commencing at the point d' , in the line I , and extending forwardly to the point d^3 , in the line I' , so arranged and positioned with relation to each other that the front and rear shoulder lines of a pattern may be determined therefrom; waist-line measurement points on said back-line from which waist measurement lines are projected at right angles one-half of a waist-line measurement and terminate in a waist-line scale, and a front neck scale having points thereon in line with the scale points in the bust and waist scales, substantially as described. 90 100 105 110 115

3. A chart for designing garment patterns having a line thereon representing the back-line of a pattern, a series of bust measurement points on said line numbered from 24 upward, bust measure lines projected forwardly from each of said points at right angles to said back-line one-half of the bust measure which terminate in a bust scale, front and rear arm-hole scales between said bust scale and said back-line, and a scale between said arm-hole scales for locating the 120 125 130

lower edge of the arm-hole, substantially as set forth.

4. A chart for designing garment patterns having thereon a back-line numbered from 5 24 upward, waist measurement points on said line from which waist measure lines project at right angles a distance of one-half of the waist measurement, said waist line points being progressively closer together as 10 they near the lower end of said back-line, and a side line scale between said waist line and back-line substantially as described.

5. A chart for designing garment patterns having a back-line, a waist line scale on said 15 back-line, a hip-line scale thereon below said

waist scale, the points in said hip-line scale on said back-line being equi-distant from each point in said waist line scale thereon, lines projecting forward from each point on said hip-line scale and terminating in an irregular front hip scale and a side hip-line scale between said front hip-line scale and said back-line, substantially as and for the purpose set forth.

In testimony whereof I affix my signature, 25 in presence of two witnesses.

GEZA J. HAVRILLA.
